(57) **CLAIM**

The ornamental design for an enclosure for portable solar charger, as shown and described.

DESCRIPTION

FIG. 1 is a front perspective view of first embodiment of an enclosure for portable solar charger;

FIG. 2 is a front view of a first embodiment thereof;

FIG. 3 is a back view of a first embodiment thereof;

FIG. 4 is a left-side view of a first embodiment thereof;

FIG. 5 is a right-side view of a first embodiment thereof;

FIG. 6 is a top view of a first embodiment thereof;

FIG. 7 is a bottom view of a first embodiment thereof;

FIG. 8 is a front perspective view of a second embodiment of an enclosure for portable solar charger;

FIG. 9 is a front view of a second embodiment thereof;

FIG. 10 is a back view of a second embodiment thereof;

FIG. 11 is a left-side view of a second embodiment thereof;

FIG. 12 is a right-side view of a second embodiment thereof;

FIG. 13 is a top view of a second embodiment thereof;

FIG. 14 is a bottom view of a second embodiment thereof;

FIG. 15 is a front perspective view of a third embodiment of an enclosure for portable solar charger;

FIG. 16 is a front view of a third embodiment thereof;

FIG. 17 is a back view of a third embodiment thereof;

FIG. 18 is a left-side view of a third embodiment thereof;

FIG. 19 is a right-side view of a third embodiment thereof;

FIG. 20 is a top view of a third embodiment thereof;

FIG. 21 is a bottom view of a third embodiment thereof;

FIG. 22 is a front perspective view of a fourth embodiment of an enclosure for portable solar charger;

FIG. 23 is a front view of a fourth embodiment thereof;

FIG. 24 is a back view of a fourth embodiment thereof;

FIG. 25 is a left-side view of a fourth embodiment thereof;

FIG. 26 is a right-side view of a fourth embodiment thereof;

FIG. 27 is a top view of a fourth embodiment thereof; and,

FIG. 28 is a bottom view of a fourth embodiment thereof.

The broken lines shown represent unclaimed subject matter and form no part of the claimed design.

1 Claim, 16 Drawing Sheets
